(57) **CLAIM**

We claim the ornamental design for an aircraft seat unit, as shown.

DESCRIPTION

FIG. 1 is a top plan view of an aircraft seat unit embodying the design;

FIG. 2 is a front view thereof;

FIG. 3 is a left side view thereof;

FIG. 4 is a top rear perspective view thereof;

FIG. 5 is a left rear perspective view thereof;

FIG. 6 is a left front perspective view thereof;

FIG. 7 is a left front perspective view thereof with leg rest portions of the seat unit in a raised position; and,

FIG. 8 is a close up rear perspective view thereof.

The features shown in broken lines form no part of the design.
